FLASH LIGHT

59 Application filed October 22, 1928. Serial No. 314,033.

This invention relates to flashlights, and more particularly to suspension means therefor, and provides improvements therein.

60 The invention provides a flashlight equipped with means for suspending it from a variety of objects, and in a plurality of positions.

The invention further provides a simple, 61 serviceable, compact and economically produced construction for the purpose described.

The invention further provides novel combinations and arrangements hereinafter set forth.

15 Several embodiments of the invention are illustrated in the accompanying drawings; wherein

62 Figure 1 is a view in side elevation of a flashlight, the lower end being shown broken away and illustrating one embodiment, and Fig. 2 is a perspective view of the cap and attached parts shown in Fig. 1.

63 Figs. 3 and 4 are perspective views of modified forms of hooks.

Fig. 5 is a vertical sectional view of a second embodiment.

Fig. 6 is a perspective view of parts of a third embodiment.

64 Referring to said drawings, numeral 10 designates a flashlight, conveniently of usual construction comprising a barrel-handle 11 and cap 12, the cap being connected to the barrel by screw-threads 13, 14, or other suitable connecting means. Numeral 16 designates the usual spring or other suitable means for making contact with the zinc bottom of the cell 18 and resiliently pressing and holding the cell into contact with the usual

65 lamp, and where a plurality of cells are used, pressing and holding these into contact with one another, all as well understood.

66 Numeral 20 designates a supporting hook. This hook 20 comprises a bill 22 arranged to 67 extend alongside and substantially parallel with the side of the barrel 11. This bill 20 is formed with or mounted upon an extension (or slide) 24 conveniently extending at right-angles or approximately right angles to said bill. The said part 24 is preferably arranged

68 to extend within and lie alongside the bottom 26 of the cap, and be thereby housed by the cap, the cap 12 for this purpose being formed with a slot or opening 28 in its side adjacent the inner face of its bottom.

69 The hook 20 is preferably made adjustable so as to extend over and closely or substantially closely embrace objects of various breadth or thickness on which it is desired (or which may be at hand) to suspend or hang 70 the flash-light. For this purpose the extension or slide 24 is made slidable in or upon the cap 12, and is conveniently formed with a longitudinal slot 30 through which extends a stud or pin 32 fastened to or upon the bottom 26 of the cap. The inner end 34 of the stud is preferably spread or upset to confine the said slide, so as to prevent the hook from canting and also to frictionally bind the slide 24 against the bottom 26 of the cap. The pin 71 and slot arrangement also serves to prevent the slide 24 being detached from the cap. Conveniently a washer 36 is interposed between the upset end 34 of the pin and the slide 24, as illustrated in Figs. 1 and 2, or, 72 as shown in Fig. 5, a plate 38 extending over and covering the slide 24 may be interposed between said parts. In the embodiment shown in Fig. 5, the spring 16, instead of resting against the inner face of the bottom of 73 the cap 12, bears against the upper face of said plate and thereby serves to prevent the spring 16 from interfering with the movement of said slide 24. Furthermore, the pressure of 74 spring 16 on the plate 38 serves to provide or augment the frictional contact of said slide with the said bottom 26 of the cap. The cap 75 may be provided with the usual annular groove 39 for receiving a convolution of the spring.

76 In order to prevent the slide 24 from being bound by the cap 12 against the lower end of the barrel 11, or against an interposed convolution of the spring 16, when the cap is screwed or otherwise attached to the said barrel, the cap is provided with a deepened portion 40 which provides a space within the bottom part thereof (when the cap is fully screwed onto the barrel or otherwise attached thereto) of greater depth than the

thickness of the slide 24, or the combined thickness of the slide 24 and the convolution or convolutions of the spring 16 which are of greater diameter than the inside diameter of the barrel 11.

5 Means are preferably provided for increasing the security with which the flashlight may be suspended from and carried upon a belt worn around the waist of a person. This 10 means as shown in Figs. 1 and 2, may comprise a tongue 44 which may be conveniently cut out of the bill 22 of the hook and bent so as to lie outside of and closely alongside of the said bill, constituting in effect an auxiliary hook. The free end of said tongue, as indicated at 46, is preferably bent so as to lie very close to the adjacent face of bill 22, so as to be forced apart when it is slipped over a belt and thereby press the belt tightly 15 against the bill 22 or confine the belt between the tongue and the bill 22.

As shown in Figs. 3, 4, 5 and 6, the bill 22 itself may be bent inwardly toward the cap, as indicated at 47, so as to lie very close to said cap, and thereby act, in a manner similar to the tongue, to press the belt tightly 20 against the cap or barrel, or both, or confine the belt between the portion 46 of the bill and said part or parts.

30 Means are also preferably provided for suspending the flashlight from a nail, screw, or the like in a horizontal position. This means conveniently comprises a bayonet-slot 48 formed in the slide 24 adjacent the bill 22.

35 As shown in Fig. 3, the slide 24 may be provided with a series of notches 50 facing the slot 30, which register with the pin or stud 32 to hold the slide 24 in a plurality of positions of extension so as to thereby hold the hook in different positions of extension. The 40 sides of the slide 24 on each side of the slot 30 may be resilient and bear frictionally against the sides of the pin or stud 32.

45 Referring to Fig. 6, the hook 20 may be formed of a piece of wire 54 looped about to form a bill 22 and a slide 34, with the parts forming the slide spaced to form the slot 30. The ends of the wire are preferably brought together to form a closed slot, as shown. Moreover, the pin 32 may be attached to a 50 plate 60, which may be and preferably is of a size to fit closely within the inside of the cap 12. With the hook formed of wire, the plate 60 is preferably bent or otherwise formed to provide a channel 62 for the said slide 24, the wire being held against lateral displacement by the sides of said channel.

60 To extend the hook to fit over objects of various width or thickness, the slide 24 is pulled out to the desired extent, the friction of the slide against the bottom 26 of the cap serving to hold the slide in the position in which it is left after being pulled out. The hook can be pushed in against the object on which it is suspended, and the object will be 65 securely held between the bill 22 of the hook

and the side of the cap, or barrel, or both, by the frictional contact of the slide 24 with the bottom 26 of the cap, as already explained.

When it is not desired to use the hook, the 70 slide 24 may be pushed entirely in so that the bill 22 lies closely alongside of the cap, and thereby provides a compact arrangement, desirable for packing and for handling.

75 The flashlight may be securely attached to and carried upon a belt around the waist of a person, in the ways already described. The other incidents of the use will be apparent from the description.

80 The invention may receive other embodiments than those herein specifically illustrated and described.

What is claimed is:

1. Suspension means for flashlights, comprising a base-cap and a hook, said hook having a slide, and a bill on the slide at the side of the cap projecting upwardly alongside of the cap, said slide being slidably mounted upon the cap cross-wise of its base and adapted to provide a space of adjustable width between said bill and the side of said cap when the slide is moved outwardly, said slide being housed within said cap, and said cap having a space between its bottom and the end of the barrel to which it is connected, which in the completely engaged position of said parts is of greater depth than the thickness of said slide. 95

2. Suspension means for flashlights, comprising a base-cap and a hook, said hook having a slide, and a bill on the slide at the side of the cap projecting upwardly alongside of the cap, said slide being slidably mounted upon the cap cross-wise of its base and adapted to provide a space of adjustable width between said bill and the side of said cap when the slide is moved outwardly, said slide being housed within said cap, said cap having a spring therein having portions of greater diameter than the inner diameter of the barrel on which the cap fits, said cap having a space between its bottom and the end of said barrel which in the completely engaged position of said parts is of greater depth than the combined thickness of said portions of said spring and of the slide. 110

3. Suspension means for flashlights, comprising a base-cap and a hook, said hook having a slide, and a bill on the slide at the side of the cap projecting upwardly alongside of the cap, said slide being slidably mounted upon the cap cross-wise of its base and adapted to provide a space of adjustable width between said bill and the side of said cap when the slide is moved outwardly, and a pin and slot connection between said cap and slide, said slide having notches opening into said slot. 120

4. Suspension means for flashlights, comprising a base-cap and a hook, said hook having a slide, and a bill on the slide at the 130

- side of the cap projecting upwardly alongside of the cap, said slide being slidably mounted upon the cap cross-wise of its base and adapted to provide a space of adjustable width between said bill and the side of said cap when the slide is moved outwardly, said slide being housed within said cap, said cap having a spring therein, and a plate between said slide and said spring.
- 10 5. Suspension means for flashlights, comprising a base-cap and a hook, said hook having a slide, and a bill on the slide at the side of the cap projecting upwardly alongside of the cap, said slide being slidably mounted upon the cap cross-wise of its base and adapted to provide a space of adjustable width between said bill and the side of said cap when the slide is moved outwardly, said slide being housed within said cap, and a plate in
- 15 said cap, said plate having a channel therein within which said slide is located.
- 20 In witness whereof, I have hereunto signed my name.

MAX E. BUCHHOLZ.
